Application filed June 14, 1886. Serial No. 205,151. Term of patent 7 years.

To all whom it may concern:

Be it known that I, CHARLES WEINBERG, of the city and State of New York, have invented or produced a new Design for Gimp or Galoon, of which the following is a specification.

This design is shown in the accompanying photograph, and it relates to the ornamental character of the gimp or galoon, especially that character of gimp or galoon known as "furniture-gimp." The body a of the gimp has a surface of ordinary appearance. Upon the body is a raised pattern, b, c, having the general appearance of a chain, the cords thereof having a direction generally longitudinal of the gimp, the cords c being close together and the cords b farther apart, so that the body of the gimp is visible between them, to produce the ornamental appearance shown in the photograph.

The design for an ornamental gimp or galoon, consisting in raised longitudinal interrupted cords upon the surface, the interrupted cords c being close together, and the cords b being farther apart and intermediate to the cords c, in imitation of a chain, substantially as described and shown.
